UNITED STATES PATENT OFFICE.

SAMUEL W. DENNY, OF DETROIT, MICHIGAN.

COMBINATION CIGARETTE AND MATCH BOX.

Application filed April 8, 1924. Serial No. 704,910.

To all whom it may concern:

Be it known that I, SAMUEL W. DENNY, a citizen of the United States, residing at Detroit, in the county of Wayne and State 5 of Michigan, have invented a new and useful Improvement in a Combination Cigarette and Match Box, of which the following is a specification.

My invention relates to a new and useful 10 improvement in a combined cigarette and match container and has for its object the provision of a device of this class which will be simple in structure, economical of manufacture, and highly efficient in use.

Another object of the invention is the provision in a combined cigarette and match 15 container of means for pressing the matches and cigarettes into close engagement with each other to maintain the same in upright 20 position.

Another object of the invention is the provision in a combined cigarette and match container of a separate compartment having its own base upon which the matches may 25 rest.

Other objects will appear hereinafter.

The invention consists in the combination and arrangements of parts hereinafter described and claimed.

The invention will be best understood by a 30 reference to the accompanying drawings which form a part of this specification and in which,

Fig. 1 is a perspective view of the invention showing the lid moved to inoperative position,

Fig. 2 is a side elevational view of the invention,

Fig. 3 is a longitudinal, sectional view of 40 the invention.

The invention in its preferred form comprises a container 7, having separate compartments 8 and 9 formed therein, the compartment 8 being adapted for the reception 45 of cigarettes 18. The compartment 9 is adapted for the reception of matches 17 which are positioned in upright position. In constructing the container it is preferred that the same may be made of the proper dimensions to receive an entire package of 50 cigarettes so that it will not be necessary to remove the same from the package before placing them in the container.

The compartment 9 is formed by a partition wall 10 which extends the full width of the container 7 and which is also provided

with a base 11, spaced from the bottom of the container proper. Mounted on the wall 10, at its upper edge is a doubled over spring metallic member so as to provide two downwardly projecting spring leaves 12 and 13, one of which is adapted to press against the matches 17 to maintain the same in upright position and the other leaf 13 is adapted for pressing against the cigarette to maintain 60 the same in upright position. It is apparent that if an entire package of cigarettes is placed in the container the need for the leaf 13 to maintain the cigarettes in upright position is dispensed with. However, its presence will not diminish to any extent the 65 utility of the container for carrying a full package of cigarettes.

In the form shown in Fig. 2 the leaves 12 and 13 are shown in their compressed position, these leaves being adapted for spreading to assume a more nearly horizontal position than shown in Fig. 2 when the same 70 are not under tension.

The container is provided with a hinged 75 lid 16 adapted to close upon the container 7 and engage the bead 16' formed thereon. This lid 16 is provided with spring hinges so that upon the release of the projection 15 formed in the container 7 from the pocket 85 formed in the lid by bulging as at 14, the lid will automatically be moved to open the container. Any suitable spring connection may be adapted for use with a lid of this 90 class.

The bottom of the container is provided with a pair of channel members 19' positioned at opposite sides adapted for the loose reception of a scratching member for striking the matches on.

With a container, such as shown, a simple structure is provided and there is furnished means for carrying cigarettes and matches in a handy, and easily accessible relative position.

While I have illustrated and described the preferred form of structure, I do not wish to limit myself to the precise form of structure shown but desire to avail myself of such variations and modifications as come 105 within the scope of the appended claims.

Having thus described my invention what I claim as new and desire to secure by Letters Patent is:

1. A container of the class described comprising a plurality of compartments, one of said compartments being of less depth than

the other and provided with a side wall; and a metallic resilient member doubled upon itself and positioned on said side wall, one portion thereof being adapted to extend in 5 one compartment for engaging material placed therein for maintaining the same in upright position and the other portion thereof being positioned in the other compartment for engaging material placed therein 10 for maintaining the same in upright position.

2. A receptacle of the class described comprising a containing portion having a plurality of compartments formed therein one 15 of said compartments being of less depth

than the other and provided with a base in spaced relation to the base of the receptacle proper; a partition wall projecting upwardly from said base for forming the other wall of the compartment; a metallic resilient 25 member doubled upon itself and mounted on the upper portion of said upwardly projecting wall, and projecting downwardly therefrom into each of said compartments, said downwardly projecting portions being normally in spaced relation at their ends to said partition wall.

In testimony whereof, I have signed the foregoing specification.

SAMUEL W. DENNY.
